Primary Examiner — Sheryl Lane(74) *Attorney, Agent, or Firm* — Merchant & Gould P.C.(57) **CLAIM**

The ornamental design for device for expanded cell confinement structure, as shown and described.

DESCRIPTION

FIG. 1 is a perspective view of a device made according to my new design;

FIG. 2 is a front view thereof;

FIG. 3 is rear view thereof;

FIG. 4 is a right side view thereof;

FIG. 5 is a left side view thereof;

FIG. 6 is a top view thereof; and,

FIG. 7 is a bottom view thereof.

The broken lines represent portions of the device and form no part of the claimed design.
